REPEATER SYSTEM.

Application filed December 24, 1925. Serial No. 77,606.

This invention relates to telephone repeater systems, and particularly to a system in which singing is prevented by a novel method of frequency selection.

Various methods have been developed to prevent singing of repeaters of the 22-type which fall within two broad classes, one of which is characterized by the employment of hybrid coils and balancing networks for the prevention of singing, and the other depends upon the frequency discrimination. This invention belongs to the latter class.

The object of this invention is to provide a 22-type repeater comprising two separate one-way amplifying circuits each of which has a band filter connected therewith, which band filters are capable of transmitting a plurality of separated bands, the filters of one circuit being complementary to the filters of the other circuit, that is to say, the bands transmitted by a filter of one circuit will be thus suppressed by the filter of the other circuit, and vice versa.

The invention has other objects which will be apparent from the following description when read in connection with the attached drawing, of which Figure 1 shows schematically a form of embodiment of the invention, and Figs. 2 and 2^A are graphs serving to illustrate the principle upon which the invention rests.

In Fig. 1, L₁ and L₂ represent sections of a signal transmission circuit intended for two-way transmission. It will, of course, be understood that suitable terminal apparatus will be connected with the lines L₁ and L₂, such as telephone subsets, in order to effect two-way transmission. A₁ and A₂ represent amplifiers in the one-way circuits of the 22-type amplifier, A₁ serving to amplify the signal received from the line L₁ for transmission over L₂, and A₂ being arranged to act in the opposite direction. BF₁, BF₂, BF₃ and BF₄ represent band filters. The transmission characteristics of the filters BF₁ and BF₂ are shown in Fig. 2, and the characteristics of BF₃ and BF₄ are shown in Fig. 2^A. These figures which represent the relation between frequency and loss, that is, attenuation of the filters, show that each filter transmits a plurality of bands of frequencies and likewise suppresses a plurality of bands lying between the transmitted

bands. Thus the filters BF₁ and BF₂ may transmit four bands, one representing the range between f₁ and f₂; the second lying between f₃ and f₄; the third lying between f₅ and f₆; and a fourth lying between f₇ and f₈. In similar manner the filters BF₃ and BF₄ transmit four bands which cover frequencies suppressed by the filters BF₁ and BF₂. Thus, for example, the filters BF₃ and BF₄ transmit a band between f₂' and f₃', which range of frequencies lies between f₂ and f₃. In like manner, the other bands transmitted by the filters BF₃ and BF₄ represent frequencies which are suppressed by the filters BF₁ and BF₂.

If it be assumed that the frequencies represented by f₁ to f₉ represent the range of the frequencies over the lines L₁ and L₂, those frequencies that come within the range of the bands transmitted by the filters BF₁ and BF₂ will pass through the amplifier A₁ and will be amplified and impressed upon the line L₂. Since these frequencies are not within the range of those transmitted by the filters BF₃ and BF₄, they will not pass through the one-way circuit in the amplifier A₂, and there can not be singing around the four-wire circuit constituting the amplifier. However, the filter BF₄ will select the bands of frequencies from those being transmitted over the line L₂, and when such frequencies are amplified by A₂, they will be impressed upon the line L₁. It will be seen, therefore, that by suitable frequency selection singing may be prevented.

If the lines L₁ and L₂ are intended for two-way transmission of speech, distortion of the speech as a result of this method of frequency selection may be minimized by increasing the number of bands transmitted by each of the filters in each of the one-way circuits, so that each important part of the speech range will be found in each one-way circuit. However, there should be, of course, no overlapping of the bands of the filters of the one-way circuits because singing would result at the frequency or frequencies lying within the zone of the overlap.

While this invention has been disclosed as embodied in a particular form, it is to be understood, of course, that such form is merely illustrative of the invention and that

it is capable of embodiment in other and different forms without departing from the spirit and scope of the appended claims.

What is claimed is:

5. 1. In a signaling system, the combination with a transmission circuit of telephone transmitters connected at different points thereon for the two-way transmission of speech thereover, a repeater circuit comprising two parallel branches connected with said transmission circuit between points of connection of the said telephone transmitters, each comprising an amplifier and a band filter, each of the said band filters being so designed and proportioned as to transmit a plurality of bands of frequencies, all of which bands lie within the limits of the speech band of frequencies, the bands transmitted by one of said filters lying between the bands transmitted by the other of said filters.
10. 2. In a signaling system, the combination with a transmission circuit of telephone transmitters connected at different points thereon for the two-way transmission of speech thereover, a repeater circuit comprising two parallel branches connected with said transmission circuit between points of connection of the said telephone transmitters, each comprising a unilateral device and a plurality of filters adapted to pass a plurality of bands of frequencies, the bands passed by the filters of one branch lying between the bands passed by the filters of the other branch, all of said bands lying within the limits of the speech band of frequencies.
15. 3. In a signaling system, the combination with a transmission circuit of telephone transmitters connected at different points thereon for the two-way transmission of speech thereover, a repeater circuit comprising two parallel branches connected with said transmission circuit between points of connection of the said telephone transmitters, each comprising a unilateral amplifier and a band filter, each adapted to pass a plurality of bands of frequencies, all of which bands lie within the limits of the speech band of frequencies, the bands transmitted by one of said filters lying between the bands transmitted by the other of said filters.
20. 4. In a signaling system of the type set forth in claim 1, the method for preventing singing which consists in selecting a plurality of bands of frequencies throughout the range of the speech frequencies being transmitted in one direction, amplifying the selected bands and transmitting them in one direction, then selecting a plurality of bands of the speech frequencies being transmitted in the opposite direction, the latter selected bands lying within the frequency spectrum between the said first selected bands, amplifying the latter selected bands and transmitting the said bands as thus amplified in opposite direction to the first selected bands.
25. 5. In a signaling system of the type set forth in claim 1, the method of preventing singing of the repeater, which consists in dividing the range of speech frequencies into a plurality of bands, selecting one group of alternate bands of the said speech frequencies for amplification and transmission in one direction, selecting the other group of alternate bands of said speech frequencies, amplifying and transmitting them in the opposite direction.
30. 6. In testimony whereof, I have signed my name to this specification this 23rd day of December, 1925.
35. HERMAN A. AFFEL.

In testimony whereof, I have signed my name to this specification this 23rd day of December, 1925.

HERMAN A. AFFEL.
